UNITED STATES PATENT OFFICE.

WILLIAM PAYNE BANCROFT, OF BOSTWICK, NEBRASKA.

WRINGER SUPPORT AND FASTENER.

1,073,947.

Specification of Letters Patent. Patented Sept. 23, 1913.

Application filed September 24, 1912. Serial No. 722,045.

To all whom it may concern:

Be it known that I, WILLIAM P. BANCROFT, a citizen of the United States, and a resident of Bostwick, in the county of Nuckolls and State of Nebraska, have invented a new and Improved Wringer Support and Fastener, of which the following is a full, clear, and exact description.

My invention relates to attachments for clothes wringers, and an object of my invention is to provide a support adapted to be clamped by the ordinary clamps of the wringer and having means to hingedly secure one end to a wash-tub, washing machine or similar support, to permit the wringer to be swung across the washing structure in position for use in connection with said structure, or swung in line with the support, the movement of the wringer to the latter position serving to take it out of the way or to bring it into a position above a wash boiler or other receptacle.

A further object of my invention is to provide a novel fastening means for the end of the wringer support opposite the hinge, of a character to hold the wringer rigid.

The invention also has for its object to provide a swinging brace having means to secure it to the wash-tub or the like, and to connect it with the wringer support in such a manner that the brace will swing with the support to a position to brace the latter when in line with the wash-tub, or to a position beneath the support when the latter is to be disposed across the wash-tub.

The distinguishing features of my invention, and the important structural elements characterizing the preferred embodiment which is illustrated as an example, will be more particularly explained in the specific description hereinafter to be given.

Reference is to be had to the accompanying drawings forming a part of this specification, in which similar characters of reference indicate corresponding parts in all the views.

Figure 1 is a perspective view showing my invention applied to a wringer, the view including fragments of washing machine and a wash boiler; Fig. 2 is a plan view of my attachment applied to a wash-tub, the wringer being omitted, and the wringer-supporting bar of my invention being shown in position across the washing machine; Fig. 2^a is a view similar to Fig. 2, but

with the wringer-supporting bar swung to a position in line with the washing machine; Fig. 3 is a horizontal section through the fastener for the free end of the swinging supporting bar, the section being indicated by the line 3—3 of Fig. 4; Fig. 4 is a side elevation of the fastening device; and Fig. 5 is a view of said device from the opposite side, and with the parts in a different position.

In constructing my attachment in accordance with the particular form given as an example of a practical embodiment of the invention, a supporting element 10 is provided in the form of a bar or board having a height and thickness to be received within the clamp members A' of a wringer A, and be secured by the clamp screws A² thereof, the said bar having a length to project when secured to the wringer beyond both ends of the latter. At one end the bar is provided with a hinge 11, which desirably is in the form of a butt hinge, one butt 12 of which is suitably secured to the end of the bar 10, the other butt 13 being advantageously of duplicate flat members formed with bottom flanges 14 having holes 14^a therein to receive screws or other fastening devices, whereby to secure the hinge to the top frame B' at the back of and above the end of a wash tub or like support B, the hinge permitting the swinging of the supporting bar 10 and the supported wringer A, to a position across the end of the washtub B, or into line with said structure, so that the wringer will be out of the way of the tub, and at the same time, if desired, be disposed above and at one side of any portable wash boiler C, or other receptacle usually employed in the wringing of washed clothes.

At the front of the frame B' of a wash-tub, washing machine or like support there is secured a fastener 15, to detachably engage the projecting free end 10^a of the supporting bar 10, as hereinafter described. A brace link 16 is provided, one end of which is adapted to be pivotally secured by any suitable fastener 17 to the frame B' or its equivalent, at a point adjacent to the fastener 15. Said link is formed with a longitudinal slot 18 extending from near the opposite end to about the center, as at 19, and at the said point 19 and also at the outer end 20 of the slot 18, the latter is deflected laterally, preferably on a curved line, as indicated clearly in Figs. 2 and 2^a. A pin or

stud 21 on the under side of the supporting bar 10 is received in the slot 18, and the arrangement is such that the link 16 will swing on its pivot 17 and move longitudinally relatively to the supporting bar 10, as the latter is swung in either direction on its hinge 11. In the position shown in Figs. 1 and 2^a, the pin locks into the lateral locking end 20 of the slot 18 and thus the link serves 10 to brace the bar 10 and the supported wringer A in line with the support B. When the bar is swung on the hinge to a position across the end of the frame B' or its equivalent, the link 16 folds beneath the 15 bar 10, parallel therewith, and above the frame B'.

It is necessary that the fastener 15 for the free end of the bar 10 be of a character to rigidly hold the said bar and the supported wringer when engaged by the fastener, and to the end mentioned I make use of a novel construction of fastening means as follows: The body of the fastener is formed of two parallel vertical plates or 25 webs 22, having bottom flanges 23 provided with holes 23^a for receiving screws or other fastening devices, and advantageously, the vertical webs may be formed in a single piece, being joined at one end near the top, 30 as indicated by the numeral 24.

The body member has a latch comprising a beveled latch head 25, and a shank 26, which is spring-actuated to yield laterally for the entrance and escape of the bar 10, there 35 being a plate spring 27, the outer end of which is secured to the latch head 25 by rivets 25^a or their equivalent, that secure the said head to the shank 26 of the latch. The spring 27 passes through a hole 28 and its 40 rear end has movement between the pair of vertical webs 22. The shank 26, with the head 25 and spring 27 has longitudinal movement on the fixed member of the fastener and relatively to the webs 22, so that 45 after the head 25 has yielded laterally to the closing of the bar 10, the latch may be drawn longitudinally to firmly clamp the end 10^a of the bar between the shoulder 29 presented by the rear end of the latch head

and a shoulder formed by a lateral flange 30 50 on one of the webs 22.

To reciprocate the shank 26 longitudinally to clamp and permit the release of the bar 10, I make use of a cam lever, the handle of which is indicated by the numeral 31, and 55 which is formed with a cam head 32 having rocking movement on a stud 33, and having a lateral flange 34 forming the cam surface, as best shown in Fig. 5. The cam flange 34 is engaged by the hooked end 36 of a strap 60 or bracket on the vertical webs 22, and the arrangement is such that by rocking the cam lever by means of the handle 31, the latch will be drawn toward and from the fixed portion of the fastener, thus moving the 65 shank 26 with the latch head 25, longitudinally.

The numeral 33^a indicates a washer.

It will thus be apparent that my improved attachment avoids the necessity of clamping and re-clamping the wringer to the end of a washing machine, for instance, and moreover, that the wringer may be brought to positions to promote convenience in the use of the washing machine or its equivalent, and for performing the various wringing operations while conveniently arranged above a wash boiler or other receptacle.

Having thus described my invention, I claim as new, and desire to secure by Letters 80 Patent:-

The combination of the supporting bar having means at one end to hingedly secure it in place, and fastening means for the opposite end of the bar, said means comprising a member to be secured in place, a latch member carried by the first member, and a device to bodily slide the latch member on the other member to tightly clamp the bar, said latch member being laterally yielding 85 to permit the entrance and escape of the bar. 90

In testimony whereof I have signed my name to this specification in the presence of two subscribing witnesses.

WILLIAM PAYNE BANCROFT.
